MODULATING SYSTEM

David G. C. Luck, Haddon Heights, N. J., assignor to Radio Corporation of America, a corporation of Delaware

Application May 24, 1939, Serial No. 275,370

5 Claims. (Cl. 250—17)

This invention relates to modulating systems, and more particularly to an improved modulator of the absorption or phase opposition type in which a constant load impedance is presented to the radio frequency output tubes so that frequency and phase distortion is reduced.

A modulating system has been proposed in which the output of an oscillation generator is connected to an antenna through an impedance inverting network, the antenna having shunted across it an impedance which is variable in response to a modulating voltage. The output of the oscillator is divided between the antenna and the shunt impedance in inverse proportion to their instantaneous impedances. The variable impedance is the absorption modulator from which the system derives its name. Such a system is described and claimed in a copending application of J. W. Conklin, Ser. No. 187,618, filed January 29, 1938, and assigned to the assignee of the present application.

Another system has been proposed in which an oscillation generator is connected to an antenna, and an auxiliary modulator tube is connected across the antenna, as in the case first mentioned, but in this case radio frequency energy is supplied to the antenna not only by the generator, but also through the auxiliary modulator tube. The phase of the auxiliary energy with respect to the directly impressed energy is varied by the modulating voltage so that the resultant radiated energy is a function of the modulating voltage. Such a system is described and claimed in a copending application of A. W. Vance, Serial No. 210,304, filed May 27, 1938, and assigned to the same assignee as the present application.

In both of the systems briefly described above, the impedance of the load to which the generator is connected varies between wide limits. Thus, during downward modulation, when the absorption modulator is taking the output load, the impedance presented to the generator through the impedance inverter is high, while, during upward modulating peaks, when the absorption or modulator tube is biased below plate current cut-off, the impedance which is presented to the generator is low. A similar effect is noted in the phase opposition system.

As a result of the wide variation of impedance across the generator, phase or frequency modulation is produced and the output tubes of the generator are not able to operate at their greatest efficiency over the entire operating cycle. In addition, there is a tendency to feed low modulation frequencies back into the power supply.

It is the primary purpose of the present invention to avoid the difficulties which have been pointed out above and to provide an absorption or phase opposition modulator in which a constant load impedance is presented to the generator output amplifier throughout the modulating cycle.

The absorption and phase opposition modulators have another common feature. In both instances, modulation is accomplished by dissipating energy in a circuit which represents a complete loss insofar as the radiated energy is concerned. Thus, in the absorption modulation system, if the downward modulation of the radiated wave is to be complete, the modulator tubes must absorb and dissipate as heat the output of the output amplifier tubes, and for intermediate degrees of modulation at least some of the generated energy is absorbed and dissipated as heat loss.

In the case of the phase opposition system, complete downward modulation of the radiated wave is obtained when the modulator tube is delivering a current of average carrier value, so that it is subject to considerable plate dissipation at a time when no modulated energy is being radiated.

It is, therefore, a further object of this invention to provide a modulation system in which the energy which has been wasted in the devices of the prior art is utilized, for example, by variably dividing a constant amount of energy between two antenna systems which preferably have different radiation patterns.

Further objects of this invention and a better understanding of its nature and operation will be set forth in the following description which is to be considered in connection with the accompanying drawing. Its scope is indicated by the appended claims.

Referring to the drawing, Figures 1 and 2 are simplified diagrams to aid in the explanation of the operation of this invention; Figure 3 is a block diagram illustrating a modulator in accordance with this invention; Figures 4 and 5 illustrate simplified forms of this invention; Figures 6 and 7 are modifications of the arrangement shown in Figures 4 and 5, and Figure 8 is the circuit diagram of a modulator.

The general arrangement and theory underlying this invention will first be explained by referring to Fig. 1. Four impedances R_1 , R_2 , R_3 and R_4 are connected in series-parallel between two terminals 9 and 11, the impedance between which is represented by R .

Writing an expression for the impedance R , it is seen that:

$$\frac{1}{R} = \frac{1}{(R_1 + R_1)} + \frac{1}{(R_2 + R_2)} \quad (1)$$

Let $R_1 = R_2 = R_0$, then it follows that

$$R = \frac{R_0^2 + R_0(R_1 + R_2) + R_1R_2}{2R_0 + R_1 + R_2} \quad (2)$$

and when $R_1R_2 = R_0^2$, substituting

$$R = R_0 \quad (3)$$

in (2), then (3)

$$R = R_0 \quad (4)$$

Thus, when R_1 and R_2 are both equal to some constant R_0 , and when $R_0^2 = R_1R_2$, from Equation 4, it is seen that the input impedance R is equal to the constant R_0 without regard to the actual value of R_1 or R_2 , so long as they maintain the required relation. It may similarly be shown that the same relation applies to the circuit arrangement illustrated in Fig. 2 under the same conditions.

If R_1 represents the impedance of an antenna, and R_2 represents the equal impedance of a second similar antenna, or an absorbing network of identical characteristics, and if R_1 and R_2 represent variable impedances which are controlled by modulating voltages, it is evident that if they are varied so that the relation $R_0^2 = R_1R_2$ is maintained, then the input impedance R will remain constant.

Referring now to Fig. 3, an arrangement is shown in which impedances R_1 and R_2 have been replaced by antennas 13 and 15, respectively; R_1 and R_2 have been replaced by modulators 17 and 19, respectively; and a generator 21 has been connected across terminals 9, 11. The generator is any suitable radio frequency source such as an oscillator or power amplifier, or the like. A modulating voltage is applied to the input of the two modulators by suitable connections to terminals 23, 25. It is now necessary to consider means for varying the impedances R_1 and R_2 of the modulators 17 and 19 so that they maintain the relation of Equation 3.

Referring now to Fig. 4, an arrangement is shown in which the modulator impedance R_2 of Fig. 1 has been replaced by a quarter wave line 27 or equivalent impedance inverting network, having at its outer end a modulator 29 whose impedance is equal to R_1 . The two impedances R_1 and R_2 are equal to the constant impedance R_0 . Thus, the two modulator impedances are alike, and may be varied simultaneously. The characteristic impedance Z of the quarter wave line is made equal to the desired input impedance of the system R_0 . Consequently, if the impedance looking into the quarter wave line, represented by the dotted symbol 31, is now called R_2' , it can be demonstrated that $R_0^2 = R_1R_2'$, which satisfies the relation which must be maintained by the two modulators R_1 and R_2' .

In the drawing, impedances R_1 , R_2 , or the specific value R_0 represent either the impedance of an antenna, or of a dissipating network. If two antennas are used they preferably have different directional characteristics so that a modulated field is produced as the output is shifted from one to the other. If a single antenna and a dissipating network are used, the antenna may be nondirectional, since the total output is divided alternately between a nonradiating network and the antenna.

The fact that modulation is produced is readily understood in connection with Figs. 1 or 2, when it is considered that, if the impedance of

R_1 becomes large when that of R_2 becomes small, the output current favors R_2 , while, when the impedance of R_2 becomes small, the output current favors R_1 . The modulating voltage thus varies the current in the antenna, or, when two antennas are employed, shifts the current from one to the other.

Various modifications of circuit arrangements may be employed, two of which are illustrated in Figs. 6 and 7. The arrangements illustrated employ several quarter wave lines, or their equivalent, and may be convenient for various reasons. In Fig. 6 one modulator R_1 is connected in series with the antenna impedance R_0 and in series with a quarter wave line 33. A second line 35 is connected in series with line 33. The second line is similar to the first except that it includes the additional impedance inverter 27. Thus, each antenna, or the antenna and the dissipating network, has been removed from the generator terminals 9, 11. Fig. 7 represents an equivalent arrangement in which similar apparatus is designated as before and will usually be the preferred arrangement.

Fig. 8 is the schematic diagram of a modulator which may be employed in connection with this invention. The modulator comprises a pair of triode tubes 37, 39 whose grid and cathode electrodes are connected together. The input modulating potential is applied between the cathode and grid electrodes. The anode electrodes are returned to cathode through suitable choke coils 43 and 45. The impedance between the two anode electrodes is a function of the applied modulating voltage, and corresponds to the impedance R_1 . Two such modulators are utilized, illustrated at 17, 19, in Fig. 3, for example, and their inputs are connected in parallel. While I have illustrated a specific modulator, this is merely by way of example, as other types will be apparent to those skilled in the art. Thus, instead of merely varying an impedance, a modulator operating on the phase opposition principle may be employed, in which radio frequency voltages are produced in series with the two antennas, the phase of said voltages with respect to that impressed across the terminals 9, 11 being varied by the modulating potential.

While I have explained this invention in its application to amplitude modulation of a radio frequency carrier, it is not to be so limited. The constant impedance system has many applications. For example, it may be used to provide a readily variable source of radio frequency voltage in connection with a signal generator. The output voltage could be taken across resistor R_1 while resistor R_2 would be within the device. Because of its constant impedance, the tendency to cause the oscillator frequency to drift as the output is varied is greatly reduced. The system is useful in many applications which require controlled variation of a current, alternating or direct, in response to a signal. The controlling signal may be either a voice representing voltage or a regular or intermittent impulse. Relays may be operated by the voltages across the fixed resistors, and the device is therefore useful as a switching relay.

I claim:

1. A constant impedance load device including separate current paths, one of said paths comprising serially connected fixed and variable impedances, and the other of said paths including a fixed impedance and a variable impedance, said fixed impedances having equal values, one of said variable impedances being connected in series with

said fixed impedance through an impedance inverter, and means for varying said variable impedances in like sense and amount to vary the relative impedances of said paths and to maintain constant the input impedance of said load device.

2. A constant impedance load device comprising two serially connected load impedances, each of said impedances comprising a fixed and a variable impedance connected in parallel, and means for varying said variable impedances in accordance with the equation

$$R_1R_2=R_0^2$$

where R_1 and R_2 are the instantaneous values of the respective variable impedances, and R_0 is the value of each fixed impedance.

3. A device of the character described in claim 2 in which at least one of said fixed impedances is an antenna.

4. A device of the character described in claim 2 in which said means for varying said variable impedances includes a source of modulating voltage and at least one of said fixed impedances is an antenna.

5. A constant impedance load device including parallel current paths, each of said paths including in series a fixed and a variable impedance, and means for varying the impedance of said paths in accordance with the equation

$$R_1R_2=R_0^2$$

where R_1 is the instantaneous impedance of the variable portion of one of said paths, R_2 is the instantaneous impedance of the variable portion of the other of said paths, and R_0 is the fixed impedance portion of each of said paths.
